UNITED STATES PATENT OFFICE.

LAFAYETTE D. CLARK, OF WATERVILLE, MAINE.

NURSING-BOTTLE ATTACHMENT.

1,343,113.

Specification of Letters Patent. Patented June 8, 1920.

Application filed August 16, 1919. Serial No. 317,947.

To all whom it may concern:

Be it known that I, LAFAYETTE D. CLARK, a citizen of the United States, residing at Waterville, in the county of Kennebec and 5 State of Maine, have invented new and useful Improvements in Nursing-Bottle Attachments, of which the following is a specification.

This invention comprehends the provision 10 of a nursing bottle, designed to prevent collapsing of the nipple and to provide a more uniform flow of milk.

It is a well known fact, that nipples when associated with nursing bottles, frequently 15 collapse resulting in an interrupted or uneven flow of milk, and sometimes to such an extent that the child sucks nothing but air through the nipple. In accordance with the present invention, use is made of an attachment for the neck of the bottle, which attachment is designed to project a slight distance within the nipple and to engage the walls thereof to prevent collapse of the latter under all conditions.

25 The nature and advantages of the invention will be better understood when the following detail description is taken in connection with the accompanying drawings, the invention residing in the construction, 30 combination and arrangement of parts as claimed.

In the drawings forming part of this specification, like numerals of reference indicate similar parts in the several views and 35 wherein:

Figure 1 is a vertical sectional view taken through the bottle and nipple showing the attachment in place.

Fig. 2 is a perspective view of the attachment.

Referring to the drawing in detail, 10 indicates the neck of the nursing bottle, the nipple 11 being of the usual well known construction. The article forming the subject matter of my invention embodies a sleeve 12 adapted to be inserted within the neck 10 of the bottle, the upper edge of the sleeve being flared and slightly rounded to conform to the curvature of the flared 45 mouth of the bottle upon which it rests. This construction provides for a smooth surface over which the nipple is arranged, and consequently prohibits injury to the

nipple. The nipple can be easily and quickly applied to or removed from the neck 55 of the bottle without any interference on the part of the advancement.

A transverse wall or partition 13 extends across the upper end of the sleeve 12 and also a slight distance within the latter. This 60 wall or partition projects beyond the opposite sides of the sleeve an appreciable distance, or in other words, a sufficient distance to engage the nipple at diametrically opposite points. The upper edge of the 65 wall or partition at the ends thereof is rounded as at 14 where it contacts the nipple, so that the latter will not be cut or otherwise injured as will be readily understood. With the attachment in place as shown in 70 Fig. 1, collapsing of the nipple 11 is prevented by means of the wall or partition 13, the latter dividing the flow of milk from the bottle, and also permitting air to enter the bottle as will be apparent. The attachment 75 is extremely simple in construction and can be manufactured and sold at a nominal cost.

While I have shown and described what I consider the preferred embodiment of the 80 invention, I desire to have it understood that I do not limit myself in this connection in that such changes may be resorted to when desired as fall within the scope of what is claimed.

Having thus described my invention what I claim as new is—

1. A nursing bottle attachment comprising a sleeve adapted to be positioned within the neck of the bottle, a partition arranged 90 transversely of the sleeve and extending within the nipple beyond the sleeve to engage the latter and prevent collapsing of the same.

2. A nursing bottle attachment comprising a sleeve adapted to be inserted within the neck of the bottle, a transverse member carried by the sleeve and projecting above and beyond opposite sides thereof, said member engaging the nipple to prevent collapsing of the latter, and the upper edge of said sleeve and said member presenting rounded surfaces where it contacts the nipple.

In testimony whereof I affix my signature. 105
LAFAYETTE D. CLARK.
